(57) **CLAIM**

The ornamental design for a tire tread, as shown and described.

DESCRIPTION

FIG. 1 is a perspective view of a tire tread;

FIG. 2 is a front view thereof;

FIG. 3 is a side view thereof;

FIG. 4 is an opposite side view thereof;

FIG. 5 is an enlarged perspective view of a section of the tire tread as defined by line 5 in FIG. 1;

FIG. 6 is an enlarged front view of a section of the tire tread as defined by line 6 in FIG. 2;

FIG. 7 is an enlarged side view of a section of the tire tread as defined by line 7 in FIG. 3; and,

FIG. 8 is an enlarged side view of a section of the tire tread as defined by line 8 in FIG. 4.

The broken lines in FIGS. 1-8 show portions of the tire tread or tire which form no part of the claimed design.

The dash-dot lines on either side of the tire tread section in FIGS. 5-8 are for the purpose of illustrating the boundary of the claimed design and form no part thereof.
